UNITED STATES PATENT OFFICE.

ERNEST LOESSER, OF BLOOMFIELD, NEW JERSEY, ASSIGNOR OF THREE-FOURTHS TO
SAMUEL JACOBSON, TRUSTEE, OF NEW YORK, N. Y.

DOP FOR HOLDING PRECIOUS STONES TO BE GROUND.

1,088,234.

Specification of Letters Patent. Patented Feb. 24, 1914.

Original application filed June 2, 1910, Serial No. 564,346. Divided and this application filed June 27, 1912. Serial No. 706,151.

To all whom it may concern:

Be it known that I, ERNEST LOESSER, a citizen of the United States of America, residing in Bloomfield, county of Essex, State of New Jersey, have invented a certain new and useful Improved Dop for Holding Precious Stones to be Ground, of which the following is a specification.

In the accompanying drawings: Figure 1, 10 is a top plan view: Fig. 2, a side elevation: Fig. 3, a vertical longitudinal section.

This new dop has a tapered end 1 in which is secured by a molding operation a stone 2 to be ground. At the other end of 15 the dop is a circular series of recesses whose center is coincident with the axis of the dop in which the stone lies. This circular series of recesses may be in the form of a toothed or ratchet wheel or ring 3 rigidly and in- 20 separably forming part of the dop being made practically integral with the body thereof by the same molding operation by which the stone is attached to the apex end of the dop. The axial line in which the 25 stone is held is co-incident with the axis of the toothed ring 3.

The described mode of forming or making this dop may be varied. Thus the dop may be cast as a slug with the stone molded in its 30 end and be by appropriate tooling reduced to form. The toothed or ratchet wheel 3 whose teeth are to be properly spaced and proportioned and may in practice be 32 in

number affords a positive means for determining the successive position to which the stone may be turned to grind successive facets of a series. 35

This dop may be used in connection with grinding or polishing apparatus described and claimed in an application filed by me June 1, 1910, Ser. No. 564,347; and is a 40 division of my application Ser. No. 564,346 filed June 2, 1910.

I claim:

1. A dop to be used in grinding or polishing precious stones comprising a tapered body at the apex end of which the stone is held and a toothed wheel at or adjacent the larger end of the body of the dop whereby the dop may be rotated through known positively determined distances for successive grinding or polishing of facets upon the stone. 45

2. A dop to be used in grinding or polishing precious stones comprising a molded tapered body in the apex end of which the stone to be operated upon is molded and a toothed wheel also molded into the body of the dop and located suitably adjacent its larger end. 50

In testimony whereof, I have hereunto 55 subscribed my name.

ERNEST LOESSER.
